United States Patent Office

Des. 202,386
Patented Sept. 21, 1965

202,386

JAR

Arnold I. Lorenzen, deceased, late of Toledo, Ohio, by Gertrude M. Lorenzen, executrix, Toledo, Ohio, assignor to Owens-Illinois Glass Company, Toledo, Ohio, a corporation of Ohio

Filed Apr. 15, 1964, Ser. No. 79,519

Term of patent 14 years

(Cl. D58—25)

FIG. 2

FIG. 2 is a top plan view thereof shown without the ornamentation for convenience of illustration.

The back not shown is the same as the front shown. The characteristic features of this design reside in the configuration shown in full lines on the drawing.

What is claimed is:

The ornamental design for a jar, substantially as shown and described.
